DESIGN FOR A DUAL PHONOGRAPH

Simon Yerkovich, Bridgeport, Conn., William J. O'Neil, Atlantic Beach, N. Y., and George W. Cameron, Westport, Conn., assignors to Dictaphone Corporation, New York, N. Y., a corporation of New York

Application March 30, 1942, Serial No. 106,380

Term of patent 14 years

To all whom it may concern:

Be it known that we, Simon Yerkovich, William J. O'Neil, and George W. Cameron, all citizens of the United States and residents, respectively, of Bridgeport, in the county of Fairfield and State of Connecticut; of Atlantic Beach, in the county of Nassau and State of New York; and of Westport, in the county of Fairfield and State of Connecticut, have invented a new, original, and ornamental Design for a Dual Phonograph, of which the following is a specification, reference being had to the accompanying drawing forming part thereof.

Figure 1 is a perspective view of the right end and front of a dual phonograph, showing our new design.

Figure 2 is a perspective view of the left end and rear of the same.

The dominant features of our design reside in the portions shown in full lines.

We claim:

The ornamental design for a dual phonograph, substantially as shown and described.

SIMON YERKOVICH.
WILLIAM J. O'NEIL.
GEO. W. CAMERON.
